(54) **SAW MILLS**

(76) Inventor: **Simon Willard**

Simon Willard, of New-York.
Letters Patent

The Schedule referred to in these Letters Patent, and making a part of the same, containing a description in the words of the said Simon Willard himself, of his improvement in the Portable Iron Gang Saw Mill.

To all to whom these presents shall come: Be it known that I, Simon Willard of the City and State of New-York, have invented or discovered a new and useful improvement in the construction of a portable Iron Gang Saw Mill; or that I have invented several new and useful improvements in Saw Mill machinery, by which the saw-mill is easily convertible from the Gang Mill to a single Saw-mill, from the single mill to a gang with any required number of saws; and adjustable with great accuracy and despatch, and by which improvements the Saw-mill is also rendered portable in regular parts, or whole when made small by means of the several improved forms of Iron newly applied to this purpose, which being bolted together make and constitute the entire Saw-mill with more accuracy, compactness, firmness, durability & despatch than was known before. And when a pair of these mills are constructed for operation in the same building, they are calculated that with sufficient power to drive one at a time, while the log is being passed upon the carriage of the other mill, is all that is wanted for the use of both mills, by driving an entire log one way, at once, passing through one gang and then sawing it the other way by passing it through the other gang to which the motion power is readily shifted for that purpose, and while the former mill is stopped to remove the said timber, and to fix another log upon the carriage, thus by driving first one mill and then the other by the same propelling power, will be a saving of expense in the engine and fuel ordinarily used. And that this specification contains a full and clear description of the construction, mode of operation and advantages of this Iron Gang saw Mill, also includes for a more clear understanding of the said improvements, certain motions and parts of the other Mill, heretofore known, but which I have designated so that my claim

as a matter of the improvement, and newly applied parts are clearly distinguishable from them. That by the construction and conformation of the improved parts in connection with the parts of the saw-mill heretofore in use.

It is made and constructed a new and useful portable door Gang Saw Mill. The several parts of this saw-mill consists of a newly constructed iron supporting frame, an improved pair of vibrating feed posts, an improved driving crank shaft and balance pulley, a newly applied pair of Pittman, an improved iron saw gate & iron improved saw stirrups, and saw bolts, several pair of improved head bolts and Mill dogs, a pair of improved log bearers, and an improved feeding apparatus which are hereinafter distinctly set forth. The newly constructed iron supporting frame is composed of a pair of strong upright cast iron side frames, on flanger plates about twelve feet in length, connected across their centres with equally strong horizontal flanger parts about half their length, which together with the upright side plates, and other necessary strengthening flanges and bars required to support the journals of the operating machinery, are respectively connected in each of the same within certain show shape, the drawings further show, but which are varied, according to the situation of mill sites, and in manner of applying the driving power, then two upright cast iron side frames are firmly fastened in an upright position about four feet apart by means of bolts and cross bars, reaching from one to the other, and by means of the horizontal parts being set in and strongly bolted upon the inner ends of a pair of large parallel carriage jills, of any required length, which are also securely fastened transversely to a sufficient number of beams, bolts, whose extremities rest upon a pair of strong side walls, of stone or timber while, these middle support may depend upon posts beneath the sawing floor of the mill, and which walls are altogether sheltered by any suitable enclosure. When these saw-mills are required to be of sufficiently small construction for the purpose of being the more easily moved, while for driving logs for feeding and for other purposes, the carriage jills, for driving short timber are bolted fast upon a short basement frame, which is drawn upon rollers, while driven by sufficient teams, or otherwise from one place to another for the purpose of being continued the more conveniently to

the timber of the forest. Then these young saw mills are erected where the situation of the driving power may require the driving crank shaft to revolve above the saw gate, the cast iron supporting frame is formed with braces and otherwise shaped as may be required to sustain the operation of the machinery above the mill or the vibrating feeder posts may be omitted to reduce the amount of the cost in driving small stuff in which case the upper part of the cast iron side frames are broad & tapering upwards with a pair of upright central flanges constructed so as to constitute stationary feeder posts to which the upright slides are fastened and adjusted by screws calculated for the force of the saw gate to vibrate upon and that my right a monitor of the improvement of this supporting frame, which I hereby claim, consists in the application of iron in the newly improved form hereinbefore described and constructed of iron as the most advantageous material to admit the original form being applicable as it is hereby applied to the purpose of constructing the gang saw mill frame patterns with greater despatch and of sustaining in a superior degree the operation of the saw mill, with more accuracy, compactness, firmness, and durability than was known before, to be so advantageously calculated for accuracy and despatch in building the saw mill frames, as well as the other parts, from patterns, and for avoiding the great cost, delay, and inconvenience of erecting high, heavy, and expensive timber mill buildings limited only to particular locations. The improved vibrating feeder posts, consists of a strong pair of upright cast iron plates, nearly the length of the supporting frame, about ten inches broad in the center with an upright flange about five inches wide cast at right angles to the inside of each plate. These feeder posts are strongly fastened parallel to each other about three and a half feet apart by means of cross bars reaching from one to the other, to which each of them are firmly adjusted by screws or otherwise, and suspended by a pair of hooks and braces fixed within their upper ends to vibrate upon a horizontal shaft whose extremities are made fast & supported on the upper end of the supporting frame, while their opposite or lower ends are forced to vibrate about two inches back and forth by means of a pair of suitable cams cast or fastened on the crank shaft.

heat to its wooden journals, which carry rollers within a pair of cam grooves, fastened to the lower end of the fender posts, or they are fastened to the upper end when the driving power is applied above, so as to be opposite to the axis upon which they vibrate. The upright flanges of these fender posts, projecting toward each other, constitute the middle slides upon which the adjusted jaws of the saw gate slide up and down when the mill is in operation, or otherwise are bolted to them for that purpose. The object of the vibration of these fender posts, as just described, for which I claim my right as inventor, consists in the advantages of driving power being withdrawn from the saw, thus leaving clear of the insect timber saw dust.

The improved driving crank shaft is a strong horizontal iron shaft about five inches in diameter from feet long, mounted with a crank in each end ten or twelve inches in length, more or less, with a cross bolt in each end driving within the bore of a pair of pitman, the journals of this crank shaft being next to the crank end adjustable to a certain number of strong boxes, cast or firmly adjusted in the lower end of the supporting frame, a large square hub, supported in cast upon the crank shaft upon which the balance pulley is fastened, a next of all steel pulley is also fastened, or cast upon the crank shaft around which a running band is forced to drive the feeding apparatus. The cam fitted to revolve within these respective cam grooves, are also cast upon the crank shaft, by which the fender posts are forced to vibrate at every vibration of the vertical saw. The improved balance pulley, four and a half feet in diameter, more or less, is a broad rim cast iron wheel weighing about one thousand pound, whose eye of the hub being sufficiently large, is placed over the crank, and keyed fast to the hub support, and which is forced to revolve between one or two hundred times per minute by means of a broad flat band, in width equal to its rim being about eighteen inches upon which it runs, connecting with it the motion of the power driver of any sufficient power by which the saw mill is forced into operation. A right is cast or bolted upon that side of the balance pulley which is opposite to the crank, sufficient to balance the saw gate and other apparatus vibrating by their connection with the motion of the pitman. The newly applied pair of pitman, are about ten feet

long with both ends similar & similar to the crank ends of the common kind. The improvement of which consists in the application of an additional pitman and new place of the operation of both in relation to their connection with this iron gang saw mill, or iron saw gate. Their lower ends being fitted to turn upon the wrists of the driving crank shaft while their upper ends vibrate upon similar wrists which project from each outside edge of the upper end of the iron saw gate, except when the driving shaft is fitted to revolve above the saw gate in order to accommodate the mill to the situation of the mill site, the lower end of the pitman then vibrates upon wrists projecting from the lower outside corners of the iron gang saw gate, or when the situation of the mill site in relation to the driving power whether by steam, water wheel, animal power is applied to the driving crank shaft by flat or round rope or chain drive or by cog wheel or by water bucket or friction wheel or otherwise by which this iron gang saw mill is forced to operate, requires the pitman to be fitted to vibrate upon a pair of wrists projecting from the corners of that end of the iron saw gate which is next to the driving shaft whether it be placed to revolve above or below the saw gate in order to avoid the burthen of two great lengths of pitman. The advantages of these two pitmans as applied to this iron saw gate consist in sawing with more or less saws on either one side or the other as occasion may require by which it is convertible from a gang mill to a single saw or double slabbin, or from a single mill to a gang by which the saw gate admits of being made narrow, therefore stronger and lighter when made of cast iron and draw a log equally large and slabbing both sides, at once by running between two draw, or two sets of slabbing draw and by a pair of pitmans being connected by wrists to the corners of the saw gate opposite to the end nearest the driving shaft, almost any place is a suitable location for a low steam saw mill to give sufficient length of pitman without the high mill floors attended with great expense in providing for the elevation of the saw logs too far above the earths level to which the common single pitman saw mills are often necessarily subjected. I hereby claim that any right of the improvement as inventor of this

newly applied pair of pitmans, consists in the application of them to the wrists of the iron draw gates of this iron gang saw mill, for the purpose of the advantages herein just set forth. The improved iron saw gate is a strong cast iron four-sided frame or plate of an oblong square from four feet in length by about four wider outside 4½ feet in length by about three & a half in width inside whose sides the broad ends being embraced in the iron casting are shaped by aid of flanges cast at right angles to the faces so as to give the required strength with as little metal as possible upon a pair of iron bars projecting from the outside edge of one end. This saw gate is adapted with four jaw bolts and jaws upon its four corners by screws to vibrate between slides of the feeden posts in a vertical manner by means of the moving pitmans upon the wrists by force of the powerful crank shaft. The upper & lower broad ends of the iron gate being about a foot in width are strengthened with curved flange plates with two pair of straight iron flanges cast upon them inner edges sustaining the stirrups by which the jaws are retained against them, or the sides may consist of round or flat wrought iron bars. The jaws indeed consist of greater notches or indentations of half an inch apart more or less, or smaller as they will admit and support at a certain distance apart from each other the bolts of the lower stirrups. Holes of the screws of the upper stirrups at any place required for hanging the jaws parallel to each other. The index notches, indentations or points are made along the upper side of the upper pair of jaw flanges the lower side of the lower pair of jaw flanges or along an iron index or steel bars made fast to the saw gate flanges for that purpose. My right of the improvement of this draw gate which I claim as inventor consists in the saw flanges and indexes against which by means of the saw stirrups the jaws are adjusted retained within the sawgate with greater accuracy & dispatch and by advantage of its being forged of iron for that purpose and for the purpose of being more firm and durable and being sooner made and to saw with more accuracy & solidity than wooden beam mill gates. By its curved flanges for giving it strength and application to this purpose as herein before described and set forth.

The improved saw slings, consists of one pair for straining each saw. The upper one being a crown slings and the lower a hock slings; these slings are made of strong cast or wrought iron whose outside is about six by seven inches, and open with their interior openings about three by four inches square, and the web one inch and three eighths thick with opening between the slings, and the hooks of the slings about three fourths of an inch wide, or just wide enough to admit the thickness of the broad ends of the saw gate, and to slide along upon the saw flanges, also another nicely adjusted narrow opening is made just wide enough to admit the thickness of the saw blade bolt so that when each saw is strained it is directed in the course it is to saw, for the purpose of dispensing with the wedges ordinarily used in adjusting saw mill saws, a pair of strong three quarter upright screw pins pass through the upper parts of the crown slings, with a square end to each by which they are secured by a socket wrench on each side of the saw gate above the flanges, and driving them nicely rounded steel points upon the sides above while the hook of the lower slings passes up against the lower index by which the saws are strained within the saw gate as required for use. The drawing and differences, further explain the form of these slings. I hereby claim my right as inventor of these new and useful saw slings, as constructed and applied to this purpose herein set forth, being of superior advantage in adjusting and straining one or more or all the saws along the index of the saw gate flanges, with great accuracy and despatch. The improved saw bolts are of an ell form as the drawings show about three fourths of an inch in diameter, and the same in length. Two or more are riveted fast in each end of the saw with the ell or other parts extending back to reach against the inside back part of the slings by which the saws are hung over as required. The advantage of these right angled bolts is in their form and application to this iron gang saw mill, so that the saws can be taken out and put in without taking the bolts out of the saws, by which the saws are adjusted with despatch. The improved head blocks consisting of two pair of different construction calculated for holding fast the mill dogs by which the dogs or large timber are securely held while driving into

various small dimensions. There is a block or about two feet in width with length sufficient to extend horizontally across the carriage to which they are fastened when required. The pair is calculated for the mill dogs to be forced by screws into the round log so as to hold each intended small piece fast at each end while they are normally jawed from end to end by a gang of any number of saws required to saw the entire log at once, the outer parts into two slabs and more or less virginian plank into a flat shape or more or less flat part ready to be turned the other way into square timber or square edged plank. This pair of head blocks consist of an upper and lower cast iron flanged plate with half inch grooves cast transversely across them inside, within which the shears of the mill dogs are driven against their shoulders and held in by bolts passing through them on either side. These saw mill dogs are half inch iron plates six or eight inches wide by about two feet in length projecting between the ends about half their length while the mill dogs of the screw head block are about one foot in length, the same thickness, and nearly the same width. The moving part of the screw head block consisting of the two plates which the short mill dogs are driven fast in grooves and is forced about six inches more or less back & forth by means of a large pair of horizontal screws which are turned within a pair of screw nuts fastened on the outer back edge of another under horizontal cast iron flanged plate bolted fast vertically upon the end of the carriage. While the moving part of this stationary, or screw head block is forced forward by the large screws to drive the mill dogs into both ends of the log it is kept down beneath a pair of horizontal slides adjusted at each end of it above projections which extend from each outer lower corner. Each end of these slides are secured fast upon the upper end of four bolts which extend through the corners of the stationary part of this head block & through the carriage to hold all fast together, while the saw head block, which is movable along the carriage to suit the various lengths of the logs is also bolted or made fast to secure the log at both ends while sawing between the teeth of the mill dogs whose upper sides are flat & may constitute the horizontal bearing upon which the timber is retained.

while sawing. Another pair of these head blocks, which are also calculated for supporting the log while sawing by this gang mill, are both constructed for the purpose of moving the timber previously flattened upon the other mill, while the ends of the log rest upon the ends of these season'd wooden bearings projecting forward. These form wooden supports or pegs in holes cast in them. They consist of two plates somewhat like those described in the first head blocks, cast with the partitions by which they are connected in the same casting together with a pair of upright flanges with suitable holes made through them, through which horizontal mill dogs are driven by the mill bar into the ends of the log by which it is held till sawed. These mill dogs are round with a sharp round hollow in the ends of sufficient size, or may be square. The other thick pair of these head blocks being calculated to extend across the carriage and carry the log or timber to be moved between two sets of slatting saws so that only one small slab or two or three weighing blank may be sawed off each side of the log at once running it through between the two sets of said saws for this purpose the cast iron part of this pair of head blocks are thick horizontal plates about ten inches square bolted upon the wood part of the head blocks. From two opposite edges of these plates a pair of upright sides about five inches with door tails, for broad sliding mill dogs to slide in back & forth when driven in the end of the log by the mill bar. By this form of these head blocks the timber is fastened upon the carriage which may or may not be sufficiently narrow to pass with the log between the two sets of saws for the purpose of squaring round timber. For the purpose of moving the log along the head blocks in sawing this staff with one or more saws. The horizontal plate of these head blocks terminate at their front and back edge with a little more than a half round hollow projecting from their inner edge sufficient to keep them down while forced by one end pinion to slide along a pair of round edge sides bolted upon the timber, of the head blocks below for that purpose, to which a rack is fixed or forced by a pinion fixed upon a transverse horizontal shaft beneath to which an index or ratchet wheel is attached by which by crank or lever. The log is forced to move along the head block and become accurately adjusted by the index to any required thickness of board, or other size timber. These square stationary plates are secured fast by bolts passing downwards through them

and through thick pieces of plank, situated with rounded ends across upon the carriage and through similar pieces of plank which catch beneath the carriage or otherwise, these plates with the other upright and round mill dogs may be bolted upon the timber head blocks of common form. The great advantage of the first and second described pair of these new and useful head blocks & mill dogs, is which I hereby claim my right as inventor of the same, consist in being formed of iron and of a new and useful form by which cast iron is applicable and hereby applied by me to the new mill for the first time, for the purpose of holding fast the timber whilst it is divided into parts by a single saw or a gang of saws; and that whenever it may be required to save the cost of making both heads the horizontal plates described in the first pair of these head blocks may be cast connected by interior partitions as described in the second pair for forming the pigeon holes or apertures with grooves, above and below to hold the shanks of the notched mill dogs by which means the wooden bearings of both kinds of mill dogs can be used in the same cast iron head blocks and the upright flanges with the holes for mill dogs to be driven through into the log and to be cast upon the upper edges, I do not claim in this specification any of the third described head block except its improved construction. The application and use in this iron gang saw mill, as herein before described, a pair of ratchet catches with which the ends of the same head block can both turn back & forth at one time by one person, consists of a handle about twenty inches long, with a pair of right and left ratchets which revolve together within a ring of the large end of the handle & a pair of right & left hands revolved on each end of a pivot passing through the handle when they are used for this purpose, only one of each hand catches in the notches, while the other is withheld in the hand of the operator, the construction of these more fully appears in the drawings.

The log braces consist of horizontal rollers about eight inches in diameter, and in length not exceeding the inside width of the carriage, each of which revolves on a horizontal shaft fixed in the upper end of a pair of uprights rising from a horizontal plate with a socket in the under side; all of these parts being connected in one entire casting. These log braces more or less are supported on the upper end of an upright broad flat timber driven fast within the socket of each casting which are oriented and lowered to sustain the timber as required by means of windlasses.

each of which consists of two inclined iron timbers beneath the floor & crossings of the carriage with a three foot hand wheel on each by which the timber is raised or lowered by a rope attached to the shaft and to the lower end of the upright timber fastened in the socket of the log bearer.

The improved feeding apparatus consists of double worm feeding machinery calculated for the purpose of advancing the carriage with the log in contact with the moving chisel when drawn through it to be unshipped to run back the carriage. It is composed of the driving crank shaft, two sets of pulleys, a pair of cone down, two horizontal cone down shaft, an upright worm shaft, two worms, two toothed wheels on carriage shaft along back & pinion. One of the sets of pulleys, is fixed upon the driving crank shaft, to drive by means of a running band the other set of pulleys, which is fixed directly opposite upon the upper cone down shaft, whose axis to the lower cone down are parallel and fitted to revolve in bore in the tailoring frame. One of the worms is fixed on one end of the lower cone down shaft, which cuts in the teeth and drives the toothed wheel fixed on the lower end of the upright worm shaft whose worm of the upper end of it runs in the teeth, and drives the toothed wheel fixed on one end of the horizontal carriage shaft whose pinion acts with the cog of the track fixed on the underside of the carriage by the operation of which when the new mill is in motion, the carriage is advanced when driving the log from back by impulse of a large grooved wheel also fixed on the end of the carriage shaft when the worm of the upright shaft is withdrawn from the teeth of the toothed wheel, for the same shaft by means of a chain running in the groove of the large grooved wheel, & in the groove of the smaller grooved wheel or sheave then revolving loosely upon the end of the horizontal worm shaft aside of another larger pulley fastened to it upon which runs a continually running band connected with the motion of the power down, or another driving pulley which runs back the carriage by tightening the chain bands, which is effected by a ^{for} tightening pulley forced by a horse or otherwise fitted for that purpose. —

For the purpose within driving open timber for giving time for the offal wood of the new mill to dry sufficiently for the fuel required for driving the engine a few spacious hand carts are required to run on rails around a circular corner, so that the wood loaded upon them can be run out from the mill.

to remain several days under shelter & to dry without unloading, except when heated under the boilers. This iron gang saw mill is put into operation by any suitable power in any manner that it may be applicable to the driving crank shaft, by hand & power down or by water or cogwheels by which winds water steam or animal power may be applied with these suitable additional agents, by which the pitman, connecting the oscillating crank with the vibrating carriage of iron or steel saws, the timber fastened upon the carriage while advanced by running bands, connecting its motion with that of the driving crank shaft. And for the purpose of driving two of these gang mills by the advantage of steam or other power only sufficient to drive one at a time is required on that account. For this purpose a line of three shafts are constructed with four crank catches one of each of them from inner ends with the middle shaft to which the driving power is first applied having its journals sufficiently long to slide in its boxes when forced back & forth by means of a forked lever for the crank catches to catch in the crank catches of first one end & then the other of the two outer shafts, whose journals are of suitable size to give the required motion, and are directly opposite the balance pulleys, on the connecting or disconnecting of these shafts for shifting the power at pleasure from one mill to the other as they may be wanted to run on stop first one mill & then the other, is effected by friction connecting boxes of the kind in common use. I have described in this specification the several parts of an entire saw mill and have designated from them what I claim as inventor of the improved parts consisting of a newly constructed iron supporting frame, an improved pair of vibrating feeder posts, a newly applied pair of pitmen, an improved iron saw gate and saw index improved saw stumps, and two pairs of improved head blocks and mill dogs, for which I ask Patent for the whole, or a part of them to be used in distinct mills, according to the manner of driving, for which I have contemplated their several uses, and that I do not ask a patent for those other parts described in distinct paragraphs to the foot of the page to which I annexed no claim, I therefore claim not any part of them in this specification, except as before these are described, neither do I claim any improvement in the saws themselves, or their up & down motion, nor the horizontal movement of the carriage, except its regular advance by a double ground

work feed called the improved feeding apparatus, which I also claim as an inventor, and have set forth further improvements that I have made for the sake of explaining those parts, which I have herein before claimed, as well as to enable persons skilled in mill building to construct and put an entire saw mill of this new construction into useful operation, I in order that the further advantages of these improvements may be fully understood, altho I may have in this specification and accompanying drawings & description referring to them been particular in the explanation of the said improvements, I have nevertheless calculated and do set forth that I have in view that the improved parts of this saw mill may be of larger or smaller dimensions and the proportions be varied to advantage from the foregoing description without materially varying the general plan of the new and useful portable iron gang saw mill, together with the iron saw mill frame having the advantage of being for the first time constructed of cast iron from patterns, and fitted up as a complete machine by which the gang saw mill can now be made in a more uniform and expeditious manner than before and hereby claiming that by the said improvement, the gang saw mill is rendered more useful and durable by these several improved forms of iron which being the only materials that would admit of the most advantageous construction & despatch, by patterns of so many regular parts thus for the first time put together that would constitute an entire gang saw mill with more accuracy, compactness, firmness, durability and despatch, than was known before. The application of these improved iron parts to this useful purpose of being not only removable from place to place, but being made of iron cast after patterns with such great despatch an accuracy as will avoid the great cost, delay and inconveniences of tedious and various mill weight calculations, in erecting high, heavy and expensive timber mill buildings and gearing for steam power, and which by this improved construction renders water power in numerous places applicable that would otherwise be useless for this purpose, thus making water mill privileges more plenty, and which renders the gang saw mill when constructed small upon this plan capable of the most advantageous use in countries where water privileges are not to be found, by being propelled by small steam engines, wind or animal power and of being removable at little expense to be continued upon

United States Patent
